CONTINUOUS CASTING APPARATUS

Norman P. Goss, Mayfield Heights, Ohio

Application March 9, 1946, Serial No. 653,285

6 Claims. (Cl. 22—57.2)

1

This invention relates to improvements in apparatus for continuously casting metal while passing a stream of metal through a die open at both ends.

An object of the present invention is to provide a die structure which may expand and contract substantially in every direction when subjected to the high temperatures encountered in casting iron, steel, and their alloys from the molten condition so as to avoid die distortion and to maintain long life and accuracy for the continuous casting apparatus while producing a casting of high-grade quality.

Another object of the invention is to provide a die the walls of which are composed of short sections supported in a novel manner and providing means for the introduction of material between the sections adapted to facilitate the movement of the metal stream through the die.

Another object of the invention is to provide novel means for supporting a plurality of die sections in alignment while permitting the relative movement in each section and between sections as is required to accommodate expansion and contraction encountered during a casting operation.

Other objects and advantages of my invention will be apparent from the accompanying drawings and description, and the essential features will be set forth in the appended claims.

In the drawings,

Fig. 1 is an elevational view of a die constructed according to my invention;

Fig. 2 is a sectional view of the same taken along the line 2—2 of Fig. 1;

Figs. 3 and 5 are fragmental sectional views somewhat enlarged and taken along similarly numbered lines of Fig. 2;

Fig. 4 is a perspective view through a portion of the die slightly exploded and with some of the parts broken away to more clearly illustrate the construction; while

Fig. 6 is an enlarged perspective view of a small filler member used in one portion of the apparatus.

My improved continuous casting apparatus will be best understood from a consideration of Figs. 1 and 4. I have illustrated a die for casting what is known in the trade as a slab, although it will be well understood by those skilled in this art that many other shapes may be cast using the same principles for construction of the apparatus, the slab being rectangular in cross-section as illustrated by the space marked 10 in Fig. 2. At the four corners of the rectangular slab are ver-

2

tical corner posts 11 each generally square in section and having a fixed mounting on a base 12. Side wall members 13 serve to close the longer sides of the rectangle, and end wall members 14 close the shorter sides of the rectangle so as to provide the central enclosed passageway 10.

In use the molten metal is fed into the top of the die by any suitable means to the passageway 10, and the metal is congealed as it passes downwardly through the die, generally aided by pinch rolls or the like which draw the congealed metal away from the bottom of the die. The rolls can do little more than hold the cast slab of red hot metal. The casting at its existing temperature will stand practically no tension. Therefore the walls of the mold must remain in almost exact vertical alignment or the bar will not come through. This present invention maintains such vertical alignment.

Referring now to Fig. 4, in the faces of the post 11 are cut grooves 11a for supporting the side wall members 13 for each section of the die. In a similar fashion other grooves 11b are cut, preferably but not necessarily at the same level as the grooves 11a, in sides of the post 11 at right angles to the first-named sides, these grooves 11b being for the purpose of supporting the end wall members 14. It will be noted from Fig. 4 that the side wall members 13 are generally rectangular in form and provided with laterally extending ears 13a at the two upper corners, these ears being adapted to slide in the grooves 11a for the purpose of suspending the side members 13 in the corner posts. The members 13 are hollow to permit the introduction of water or other cooling liquid, but since the details of this cooling system have no further connection with the present invention, they will not be described here. In like manner, the end wall members 14 have at their upper corners the laterally extending ears 14a which are adapted to slide in the grooves 11b so as to suspend the members 14 in the corner posts 11. Extending inwardly from each end member 14 beyond the faces of the corner posts is a tongue portion 14b which is the full depth of the end member and of such a width that it just fits slidably between the inner faces of the parallel side wall members 13.

Each of the side wall members extends downwardly to a plane 13b which is slightly spaced from the top face 13c of the next member beneath it, and this space is utilized for the introduction of a "lubricant" by which term both here and in the claims I intend to indicate any material which will facilitate the passage of the con-

gealing metal along the inner walls of the die. The manner of introducing this lubricant will be described later. In like fashion, the end wall members 14 extend downwardly to a plane 14c which is vertically spaced above the top face 14d of the next member below. This leaves a narrow zone between vertically aligned end wall members for the introduction of lubricant as will be later described. It is obvious also that with the space left between 13b and 13c in the case of the side wall members and between 14c and 14d in the case of the end wall members, vertical expansion and contraction of all these members is possible. This vertical expansion and contraction will slightly change the dimension of the lubricant feeding port, but this is of no practical importance.

There is a slight play between the end walls 13d of the members 13 and the adjacent faces of the corner posts 11. This clearance space 35 (Fig. 3) permits horizontal expansion and contraction of the side wall members 13 in the direction of their length. These side wall members are held in position by the anchor plates 16 which extend across the longer dimension of the die opposite each feeder port and are secured to the corner posts 11 by means of bolts 17.

Across the shorter dimension of the die at each of the feeder ports is secured an anchor plate 18 which is fastened to the corner posts 11 by means of the bolts 19 which pass through slotted openings in the plate 18. This permits expansion and contraction of the end wall members 14 in the direction of their length, that is to say, across the shorter ends of the rectangle. This expansion and contraction is resisted by means of bolts 20 which extend through parallel anchor plates 16 on opposite sides of the die and outside of the end members 14. Beneath the bolt head of each bolt 20 is secured a short, stiff, helical spring 21 which always maintains a tension across the shorter dimension of the die.

Means is provided for introducing lubricant at each of the feeding ports previously described. This lubricant may be finely comminuted and dry, or it may be in paste form, or it may be in block form. For purposes of illustration only, and by no means as a limitation, I have shown finely comminuted material 22 arranged to be fed through the side feeder ports 23 and lubricant in block form 24 to be fed through the end feeder ports 25. At the side feeder ports, hoppers 26 are mounted on the anchor plates 16, and the finely comminuted material 22 is placed in each hopper. Communicating with the bottom of each hopper is a passageway 26a which registers with the feeder port 23. A plunger 27 fits slidably into the passageway 26a, and means is provided for pressing upon the plunger 27 to feed the lubricant material through the port 23. In the form here-
shown, a bell crank 28 is pivotally mounted on the hopper 26 and is urged by a weight 29 in a direction to drive the plunger 27 inwardly. Obviously, by moving the bell crank 28 in a clockwise direction, as viewed in Fig. 5, the plunger 27 may be drawn outward far enough to permit additional material 22 to be discharged from the hopper 26 into the passageway 26a.

Referring now momentarily to Figs. 2, 4, and 6, it will be noted that each side feeder port 23 is not the full length of the longer dimension of the die because of the end tongues 14b. I, therefore, use the small filler members 30 of Fig. 6 to fill in these corners and to guide the lubricant as desired as clearly shown in Figs. 2 and 4. Each member 30

may consist of an L-shaped strip of metal or the like 30a to which is attached a liner 30b of a resilient sealing material adapted to withstand heat such as asbestos, brake lining, or very thin metal.

5 The vertical depth of one of these feeder ports 23 or 25 is approximately one-quarter ($\frac{1}{4}$) inch, and I find that a vertical dimension of the strip 30a of approximately three-sixteenths ($\frac{3}{16}$) inches with the resilient liner extending beyond the upper and lower edges will serve my purpose.

At the end feeder ports 25, I have shown means for feeding the lubricant blocks 24. To each anchor plate 18 is secured a hopper 31 as best seen in Figs. 1 and 3. The bottom of each hopper 15 communicates with a horizontal passageway 31a which registers with the feeder port 25. A reciprocating plunger 32 fits slidably into the passageway 31a. A bell crank 33 and a weight 34 urges the plunger 32 inwardly. Preferably, means 20 is provided for supporting the blocks 24 in the hopper 31 so that they will feed in a proper manner to the passageway 31a. The means here shown comprises the parallel walls 31b between which the blocks 24 are adapted to slide. Upon 25 oscillation of bell crank 33 in a counterclockwise direction as viewed in Fig. 3, the plunger 32 may be drawn outwardly far enough to permit an additional block 24 to drop into the passageway 31a. The rolls can do little more than hold the cast slab of red hot metal. The casting at its existing temperature will stand practically no tension. Therefore the walls of the mold must remain in almost exact vertical alignment or the bar will not come through. This present invention maintains such vertical alignment.

It will be clear now from the above description that I have provided a die having a central passageway open at both ends and in which the die walls are composed of relatively short sections as measured in the direction of the length of the die, say of the order of six to twenty-four inches. The vertically aligned side walls on any one side of the die have lubricant feeder ports between them, and this permits vertical expansion of the side wall sections. At the same time, two expedients are provided for permitting expansion of a side wall in a horizontal direction. In the case of the longer walls 13, I have left the slight space 35, previously described, which permits expansion in this direction. The space here cannot permit the escape of molten or slightly congealed metal from the die passageway because the spaces 35 are overlapped by the tongues 14b as clearly seen in Fig. 3. The other expedient is the bolt-and-slot connection described in connection with plate 18 and bolts 19 together with the expansion bolts 20 which takes care of the expansion across the smaller dimension of the die horizontally measured. At the same time the corner posts 11 maintain vertical alignment of the die sections, and the introduction of lubricating material at the ports 23 and 25 between the sections aids the movement of the metal column through the die as described in my Patent Number 2,225,373, granted December 17, 1940.

In the construction of the die as described in this application, I may choose to use the step construction described in my above-mentioned 70 copending application in which case the cross-sectional dimensions of the die would be increased slightly at each feeder port so that the passageway 10 becomes slightly larger at various zones as the metal moves downwardly in the die. Such details are not shown here because the

amount of increase at each step is too small to show on drawings of this nature.

What I claim is:

1. In a die open at both ends and providing a central longitudinally extending passageway therethrough for guiding a column of metal while it congeals during a continuous casting operation, the combination of fixed vertically extending posts parallel to the longitudinal dimension of said die, plates extending between said posts and forming side walls for said die completely enclosing the sides of said passageway, each of said side walls being composed of a plurality of vertically aligned plates, each of said plates having end projections at its upper edge extending laterally outwardly, there being horizontally extending grooves in the posts at the ends of the side walls, said end projections extending into said grooves, whereby said projections interlock with said posts and substantially prevent vertical movement of the associated plate, means holding said plates against movement away from said central passageway, one of said plates in a given wall extending downwardly from said upper edge toward another of said plates in the same wall and stopping short of said other plate to provide a clear space between said plates, whereby said one plate may expand downwardly into the adjacent space without warpage.

2. A die as in claim 1 wherein said passageway is rectangular in section having two mutually opposed pairs of side walls, and one pair of said side walls having portions telescopingly fitting between and closely against the inner surfaces of the other pair of said side walls.

3. A die for the continuous casting of metal, comprising coacting vertical walls entirely surrounding a central passageway on its several sides and fixed vertical posts spaced about said walls and supporting them, said passageway being open at the top for the introduction of molten metal and being open at the bottom for the continuous removal of molded metal, said wall on each of said sides comprising substantially vertically aligned separate wall portions with a free space between them permitting vertical expansion of said wall portions, inter-engaging parts between said wall portions and posts including horizontal projections coacting with recesses of limited vertical extent holding a horizontal zone of each of said wall portions fixed against vertical movement, and means for filling said spaces between vertically aligned wall portions with lubricant adapted to contain metal within the die passageway and to provide lubrication between the congealing metal and said walls.

4. A die for the continuous casting of metal comprising four fixed vertical posts at the four

corners of a rectangle, side and end wall members substantially enclosing the four sides of said rectangle leaving a central passageway open for the passage of metal, each side of said rectangle being composed of a plurality of vertically aligned separate wall members, inter-engaging parts between said wall members and posts including horizontal projections coacting with recesses of limited vertical extent holding said wall members against vertical movement and against horizontal movement away from said central passageway, there being slight spaces between vertically aligned wall members on each side of said rectangle, said side wall members having clearance to expand in the general plane of each of said side walls, and said end wall members having a telescoping fit between the inner surfaces of said side wall members.

5. A die as in claim 4 including means for filling said spaces between vertically aligned wall members with lubricant adapted to contain the metal in said central passageway there adjacent.

6. A die for the continuous casting of metal comprising four fixed vertical posts at the four corners of a rectangle, side and end wall members substantially enclosing the four sides of said rectangle leaving a central passageway open for the passage of metal, each side of said rectangle being composed of a plurality of vertically aligned separate wall members, inter-engaging parts between said wall members and posts including horizontal projections coacting with recesses of limited vertical extent holding said wall members against vertical movement and against horizontal movement away from said central passageway, there being slight spaces between vertically aligned wall members on each side of said rectangle, and means yieldably clamping two of said wall members on opposite sides of said rectangle between their supporting posts, whereby said two yieldingly clamped wall members may expand each in its own general plane.

Certificate of Correction

Patent No. 2,510,100

June 6, 1950

NORMAN P. GOSS

It is hereby certified that error appears in the printed specification of the above numbered patent requiring correction as follows:

Column 4, line 29, beginning with "The rolls can" strike out all to and including the words and period "vertical alinement." in line 35, and insert instead the following—

The blocks 24 of graphite or the like retain metal in the mold passageway and provide mold walls between the edge 13b of one wall section and the edge 13c of the adjacent wall section below it.;

and that the said Letters Patent should be read as corrected above, so that the same may conform to the record of the case in the Patent Office.

Signed and sealed this 10th day of October, A. D. 1950.
